UNITED STATES PATENT OFFICE.

LAWSON B. SHELTON, OF LOS ANGELES, CALIFORNIA.

FOLDING CRIB.

1,197,961.

Specification of Letters Patent. Patented Sept. 12, 1916.

Application filed June 7, 1915. Serial No. 32,485.

To all whom it may concern:

Be it known that I, LAWSON B. SHELTON, a citizen of the United States, residing at Los Angeles, in the county of Los Angeles and State of California, have invented a new and useful Improvement in Folding Cribs, of which the following is a specification.

The object of my invention is to construct 10 a folding crib, which is simple in construction and which when folded up is compact and neat in appearance and combines a seat and wardrobe drawer in connection therewith, and my invention consists of the novel 15 features herein shown, described and claimed.

The accompanying drawings illustrate the invention, in which.

Figure 1 is a side elevation of my improved folding crib, as it appears looking 20 in the direction of arrow 1 in Fig. 2, showing the crib in position for use. Fig. 2 is a top plan view, as seen looking in the direction of arrow 2 in Fig. 1. Fig. 3 is a vertical 25 central sectional view, taken upon the lines 3—3 of Figs. 2 and 4, showing the crib in folded position. Fig. 4 is a transverse section taken upon the line 4—4 of Fig. 3, the 30 crib being shown in its folded position, as in Fig. 3. Fig. 5 is an enlarged fragmentary perspective view showing the hinge between the crib frame and head board.

Referring more particularly to the drawings, the preferred embodiment of my invention comprises the housing or supporting frame 1, which is composed of the side members 2 and 3, the bottom 4, front 5, and supporting arms 6 and 7. Vertical guide ways 8 and 9 are formed upon the inner 35 faces of the side members 2 and 3 and face each other, said guide ways being parallel and extending from the bottom 4 of the housing to the top of said side members.

The bed frame 10 is adapted to swing 40 between the side members 2 and 3, and consists of the side boards 11 and 12, head board 13 and foot board 14. A guide rod 15 extends across the upper end of the head board 13 and is secured thereto by screw eyes 16. A hinged head board 17 is hinged 45 attached to the guide rod 15 and extends upwardly and is hinged attached at its upper end to a second guide rod 18, by screw eyes 19. Said guide rods being 50 longer than the width of the bed frame and

extending into the vertical guide ways 8 and 9.

A pair of supporting legs 20, 21 are rigidly attached together by the brace 22 and hingedly connected to the upper end of the 60 foot board 14, by the hinges 23 and 24. A pair of longitudinal connecting bars 25 and 26 are pivotally connected to the upper ends of the supporting legs 20 and 21, and to the guide rod 18. A second pair of longitudinal connecting bars 27 and 28 are connected to said legs 20 and 21, below the bars 25 and 26, and to the intermediate portion of the head board 17, said bars being approximately parallel with each other. 79

A transverse supporting bar 29 extends across the head end of the bed frame 10, and is rigidly attached to the side boards 11 and 12, said bar extending out beyond the bed frame, as shown in Fig. 2, and resting upon the supporting arms 6 and 7 of the side members 2 and 3. This supporting bar 29 supports the head end of the bed frame and forms the fulcrum upon which the bed rotates. The underside of said supporting bar being rounded as indicated at 80 30, to facilitate movement thereof in raising or lowering the bed frame. A seat 31 is hingedly attached to the outer ends of the supporting bar 29 and the seat back 32 is 85 rigidly attached to the underside of the bed frame 10 against said supporting bar 29. When the bed is in open position as shown in Fig. 1, the weight of the bed frame rests upon the supporting bar 29 and not upon the 90 seat 31 and back 32.

A drawer opening 33 is formed between the side members 2 and 3, at their forward ends, for the reception of a drawer 34, said drawer opening extending from one side to 95 the other, so that the drawer may be reached from either side. The drawer is open at the top as shown in Figs. 3 and 4, so that when the bed is in folded position access may be had thereto by swinging up the hinged 100 seat 31.

Fig. 3 shows the crib in folded position and in the operation of swinging it to its open position, the supporting bar 29 slides forward upon the arms 6 and 7 until the 105 guide rod 15 swings into alignment with said supporting bar, and then said supporting bar slides back to the position shown in Fig. 1.

The longitudinal bars are hinged to the 110

legs and head board in such relation to each other that when the bed is swung to its open position, the legs assume a vertical position to support the outer end of the 5 bed frame, and when swung to its closed position they remain in this position and extend alongside the connecting bars, as shown in Fig. 3.

The connecting bars 25, 26, 27 and 28, 10 and the brace 22, form a folding super-structure above the bed frame and serve the double purpose of bracing the legs, when the crib is in position for use, and prevent the child from climbing or falling out of 15 said crib.

It is obvious that I have constructed a crib which is convenient and compact and which combines a seat and wardrobe drawer in connection therewith, so that clothing 20 and other necessities may be kept in a convenient place near the bed.

What I claim and desire to secure by Letters Patent of the United States is—

1. In a folding crib construction, a hous- 25 ing comprising side members, a plurality of vertical parallel guide ways in the side members, a bed frame adapted to swing between said side members, a guide rod upon the head end of said frame and ex- 30 tending into a pair of said guide ways, a head board hingedly connected to said guide rod, a second guide rod hingedly connected to the upper end of the head board and extending into the other said guide ways, 35 legs hingedly connected to the foot end of the bed frame and connecting bars pivotally connecting the legs and head board together.

2. In a folding crib construction, a hous- 40 ing comprising side members, a bed frame adapted to swing between said side members, supporting arms upon said side mem-

bers, a supporting bar upon the bed frame adapted to rest upon said supporting arms, a plurality of guide ways upon the inner 45 faces of the side members, a hinged head board upon one end of the bed frame, legs hinged to the other end of said frame, pintles extending outwardly from the head board into the guide ways and connecting 50 bars connecting said head board and legs together.

3. In a folding crib construction, a hous- 55 ing comprising side members, a bed frame adapted to swing between said side members, a plurality of guide ways in said side members, a head board hingedly connected to one end of said bed frame and legs hingedly connected to the other end, pintles 60 upon said head board extending into said guide ways, connecting bars connecting the head board and legs together and a supporting bar upon the head end of the bed frame resting upon said side members, so that when the bed is rotated to a vertical position 65 the supporting bars and legs fold together against said bed frame.

4. A folding crib construction comprising 70 side members, a bed frame adapted to swing between said side members, arms upon said side members, a supporting bar upon said bed frame adapted to rest upon said arms and forming the fulcrum upon which the bed frame is rotated, a head board hingedly connected to one end of said bed frame and 75 legs hingedly connected to the other end, and means connecting the head board and legs together, so that when the bed frame is in its folded position the legs assume a vertical position above the side members.

LAWSON B. SHELTON.
